CLAIM

The ornamental design for a surface pattern applied to a putter golf club head, as shown and described.

DESCRIPTION

FIG. 1 is a perspective top plan view of a surface pattern applied to a putter golf club head showing our design; and, FIG. 2 is a top plan view thereof.

The broken lines in the figures are used to illustrate the unclaimed portions of the invention and form no part of the claimed design.

1 Claim, 2 Drawing Sheets
